United States Patent Office.

ABIJAH JOHNSON, OF WEST NEWTON, INDIANA.

Letters Patent No. 64,328, dated April 30, 1867.

STRIKING-ATTACHMENT TO CLOCKS.

The Schedule referred to in these Letters Patent and making part of the same.

TO ALL WHOM IT MAY CONCERN:

Be it known that I, ABIJAH JOHNSON, of West Newton, in the county of Marion, and State of Indiana, have invented a new and useful improvement in clocks, which I have called a "Teacher's Monitor;" and I do hereby declare that the following is a full and exact description thereof, reference being had to the accompanying drawing, making part of this specification.

My invention relates to indicating and announcing the programme of exercises or commencement of recitation of the several classes during the hours of school, and to this end consists in substituting for the hour-hand of a clock having striking-mechanism a flat ring, which is spaced and figured similar to but in the reverse direction from the clock-dial, said ring being perforated with small holes in which to insert pegs that operate the striking-mechanism according to the programme of exercises as laid down by the teacher, so that no class shall by oversight be allowed to occupy more than its allotted time, that each may receive its due share of attention, and that the school may be conducted with system and order.

Figure 1 is an elevation of a clock-face or front with my improvement attached.

Figure 2 is a vertical transverse section through the centre of the clock.

Figure 3 is a representation of the wheels and levers of the striking-machinery of a clock, showing in red lines the change required in the levers so that the striking-works may be set in operation by my attachment.

My improvement may be attached to any clock having striking-mechanism, but in clocks that strike the number of hours the mechanism that effects this will have to be changed so that the clock will strike but one, as is common with many clocks now.

A is the ordinary clock-dial, D the minute-hand. The hour-hand is removed, and in its stead a flat ring, B, is employed, having a centre provided with a short tube to fit on to the hand-post as the hour-hand is attached. From the centre arms radiate to the ring to support and carry it. On the arm under the 12 the hour-hand may be painted, and will indicate the hours in the usual manner. The ring B is spaced and figured similar to the dial, but in the reverse direction. The ring is perforated with small holes, in this case five minutes apart, or twelve between the hours, as shown in fig. 1, in which to insert pins to trip the striking-wire and operate the striking-machinery. In clocks that strike the hours the striking-works are set in motion by the lever or striking-wire F, fig. 3, being actuated by the little pin or bent wire g in the hand-post once in each revolution of the post, being once an hour.

In order to apply my improvement and cause the clock to strike at the time set for the commencement of the several exercises, all that is required is to bend the lever or striking-wire F, fig. 3, upward, and bend the point outward, as shown at E, figs. 2 and 3, so that it may be actuated by the pins C in the ring B. These pins trip the lever E and set the striking-works in motion in the same manner as the pin or bent wire g in the hand-post, and will cause the clock to strike as often as a pin, C, is carried by the revolution of ring B up to trip the lever E. The teacher may commence his exercises at any desired hour, and time his programme at pleasure, and by inserting pins C in the holes in ring B cause the clock to announce the same without further trouble or attention. Suppose the exercises to commence at nine o'clock, a pin, C, inserted at that figure will cause the clock to strike at that hour. If this exercise is to take up fifteen minutes of the time, and another to commence at its expiration, a pin inserted in the third hole in ring B, toward the 10, from the first, will cause the clock to strike as before, and so on until the time allotted to the several exercises has expired. When the teacher has once arranged his programme and set the pins accordingly, no other attention is required than to keep the clock wound up until he desires to make a change. Although I have shown the holes spaced five minutes apart, as being sufficient for practical purposes, any other spacing may be used that is desired.

I claim the ring B, spaced and figured as shown, and perforated for the insertion of pins to operate the striking-machinery of a clock, and in combination therewith the movable pins C, substantially as and for the purpose set forth.

ABIJAH JOHNSON.
